(57) **CLAIM**

The ornamental design for a muscle stimulator as shown and described.

DESCRIPTION

FIG. 1 is a left-side elevational view of a muscle stimulator showing my new design;

FIG. 2 is a front elevational view thereof;

FIG. 3 is a Right-side elevational view thereof;

FIG. 4 is a rear elevational view thereof;

FIG. 5 is a top plan view thereof;

FIG. 6 is a bottom plan view thereof; and,

FIG. 7 is a front and right side perspective view thereof. The broken line showing portions of the muscle stimulator forms no part of the claimed design.
